UNITED STATES PATENT OFFICE.

EDWARD T. SCHOONMAKER, OF NEW YORK, N. Y., ASSIGNOR TO J. S. CONOVER & CO., OF SAME PLACE.

DESIGN FOR A FIRE-PLACE FRONT.

SPECIFICATION forming part of Design No. 15,836, dated February 17, 1885.

Application filed December 5, 1884. Term of patent 7 years.

To all whom it may concern:

Be it known that I, EDWARD T. SCHOONMAKER, of the city, county, and State of New York, have invented a certain new and ornamental Design for Fire-Place Fronts; and the following is declared to be a description of the same.

My design is fully shown in the accompanying photograph.

10 In this design the frame, the basket, the crown-piece, and the fender are especially designed to go together in the production of an artistic effect. The fire-place frame has an outer plain surface, *a*, and next to it an echinus molding having depressions or knobs or eggs at *b*. There are moldings at *c d*, between which is a panel at *e*, filled with a serpentine design of stems, leaves, and scrolls.

15 The design of the basket consists of the lower plain and figure molding at *f*, and the upper plain bar, *g*, and the perpendicular designs in oak-leaves at *h*.

20 The design of the convex crown-piece consists of the lower polished base, *i*, and molding *k*, the plain upper rail, *l*, and the convex lattice-work *m*, and intermediate oak-leaf design at *m'*.

25 The design of the fender consists of the flat polished plate *n*, having diverging lines, the surrounding frame having a plain surface, *o*, and molded edges *o' o'*, the base-molding *p*, and the convex molding *r*, having echinus or-

naments, as shown. At the corners of the fender are ornamental pillars *s*, as shown. Between these pillars there are the twisted ornamental bars *v*.

35 In this fire-place front the ornamental designs of the frame, grate, crown-piece, and fender harmonize so as to produce an artistic effect as a whole, the ornaments *b* of the frame 40 and *r* of the fender being similar, the leaf designs *h* of the basket, *m* of the crown-piece, and *s* of the fender-posts harmonizing with the leaf designs *c* of the frame.

45 I claim as my invention—

1. In a design for a fire-place front, the ornamental frame consisting of the surface *a*, echinus ornaments *b*, moldings *c d*, and the panel *e* of serpentine stems and leaves, as shown.

50 2. In a design for a fire-place front, the design consisting of the ornamental echinus-moldings *b r* and the oak-leaf ornaments, substantially as described and shown.

3. The design for the ornamental fire-place 55 front, consisting of the frame, basket, crown-piece, and fender, substantially as described and shown.

55 Signed by me this 1st day of December, A. D. 1884.

EDWARD T. SCHOONMAKER.
